(57) **CLAIM**

The ornamental design for an air pump housing, as shown and described.

DESCRIPTION

FIG. 1 is a perspective view of an embodiment of an air pump housing,

FIG. 2 is a front view thereof,

FIG. 3 is a rear view thereof,

FIG. 4 is a left-side view thereof,

FIG. 5 is a right-side view thereof,

FIG. 6 is a top view thereof; and,

FIG. 7 is a bottom view thereof.

The broken lines are for purposes of illustration only and do not form a part of the claimed design.
